GRINDING MACHINE

Wallace H. Wood and Carl G. Flygare, Worcester, Mass., assignors to Norton Company, Worcester, Mass., a corporation of Massachusetts

Application April 29, 1936, Serial No. 76,900

8 Claims. (Cl. 51—105)

This invention relates to grinding machines, and more particularly to a grinding machine arranged to grind a plurality of faces on a work piece.

- 5 One object of this invention is to provide a simple thoroughly practical grinding machine for grinding a plurality of faces on a work piece. A further object of this invention is to provide a hydraulically driven grinding machine which is adapted to grind the peripheral and end face of a work piece in a single operation.

15 It is a further object of this invention to provide an angularly arranged wheel unit with a grinding wheel which is arranged to grind both the peripheral and end face of a work piece. It is a further object of this invention to provide a grinding machine in which the grinding wheel is moved toward and from the work piece to grind a peripheral face and the work piece is moved longitudinally in timed relation with the wheel slide movement to grind the end face thereof. Other objects will be in part obvious or 20 in part pointed out hereinafter.

The invention accordingly consists in the features of construction, combinations of elements, and arrangements of parts, as will be exemplified in the structure to be hereinafter described, and the scope of the application of which will be indicated in the following claims.

- 30 In the accompanying drawing in which is shown one of various possible embodiments of the mechanical features of this invention,

Fig. 1 is a combined fragmentary plan view, having parts broken away and shown in section, to more clearly show the construction and a piping and wiring diagram to show the operation of the mechanism.

A grinding machine has been illustrated in the drawing comprising a base 10 which is arranged to support a transversely movable wheel slide 11 on the usual V-way 12 and flat way 13. The wheel slide 11 supports a rotatable wheel spindle 14 mounted in bearings (not shown). The wheel spindle 14 supports a grinding wheel 15 on its outer end. The wheel spindle 14 may be rotated in any well-known manner, such as by means of an electric motor 16 mounted on the upper surface of the wheel slide 11. The motor is provided with a rotor shaft 17 supporting a driving pulley 18 which is connected by driving belt 19 with a pulley 20 mounted on the end 40 of the wheel spindle 14.

The base 10 also supports a longitudinally movable work supporting table 25 which is arranged to slide longitudinally on the base 10 on a

V-way 26 and **flat way 27**. The table 25 carries a headstock 28 and a footstock 29 which are provided with centers 30 and 31 respectively which serve to rotatably support a work piece 32 in operative relation with the grinding wheel 15. 5 The headstock is provided with a rotatable spindle 33 which is driven by means of a pulley 34 from a well-known source of power, such as a motor on the headstock (not shown) or an overhead drive (not shown). 10

The wheel slide 11 is arranged to be moved transversely toward and from the work supporting table 25. In the preferred construction, a hydraulically operated feeding mechanism is provided comprising a cylinder 40 which is fixed to the base. The cylinder 40 carries a slidably mounted piston 41 which is connected by a piston rod 42 with the wheel slide 11. A fluid pressure system is provided to supply fluid under pressure to either side of said cylinder to cause a forward or rearward movement of the grinding wheel 15. This system comprises a fluid pressure reservoir 43 which is preferably located within the base of the machine. Fluid is drawn from reservoir 43 through a pipe 44 by means of a geared pump 45 which forces fluid through a pipe 46 to a feed controlling valve 47. The feed control valve is preferably a balanced piston type valve comprising a valve stem 48 having formed integrally therewith valve pistons 49, 50, 51, and 52 which are slidably mounted within the valve casing 47. In the position of the parts, as illustrated in the drawing, fluid under pressure passing through the pipe 46 enters a valve chamber 53 and passes through a passage 54 into a cylinder chamber 55 to cause the piston 41, the piston rod 42 and the wheel slide 11 to move forward so as to cause an infeeding movement of the grinding wheel 15.

During the forward feeding movement, fluid within a cylinder chamber 56 is exhausted through a passage 57 into a valve chamber 58 which is located between valve pistons 51 and 52 and exhausts through a pipe 59 into the reservoir 43. When the valve is shifted into a reverse position, fluid under pressure from pipe 46 will pass into valve chamber 53 between the valve pistons 50 and 51 and pass through the passage 57 into the cylinder chamber 56 to move the piston 41 and the wheel slide 11 rearwardly. A manually operable control lever 60 is pivotally mounted on a stud 61 which is preferably supported on the base 10 of the machine. The lever 60 is provided with a stud 62 which is connected to the forward end of an extension 63 of the piston rod 48. When the lever 60 is in the 40 45 50 55

position illustrated in full lines in the drawing, fluid under pressure will be admitted to cause a forward feeding movement of the grinding wheel. When the lever 60 is shifted into dotted line position 60a, a rearward movement of the wheel will be obtained.

In order to automatically reverse the valve 47 in timed relationship with the other movements of the machine parts, an automatic mechanism is provided comprising an electrically operated solenoid 65 which is connected to a projecting arm 66 fixed on the extension 63 of the valve stem 48. When the solenoid 65 is energized, it serves to move the valve rearwardly into the reverse position from that shown in Fig. 1 to cause a rearward feeding movement of the grinding wheel 15.

The fluid under pressure entering the cylinder chamber 55 serves to cause a rapid approaching movement of the grinding wheel 15. In order to produce a slow controlled infeeding movement of the grinding wheel, a dash pot mechanism is provided which serves to modify the movement of the wheel slide as produced by the piston 41 and cylinder 40. The dash pot mechanism disclosed herein is identical with that shown in the prior United States patent to Silven No. 2,023,704 dated December 10, 1935. A dash pot piston 70 is slidably mounted on the outer end of the piston rod 42. The dash pot piston 70 is contained within a dash pot cylinder 71 fixedly mounted on the end of the cylinder 40. A spring 72 serves to normally hold the dash pot piston in a rearward position. On the forward feeding movement of the grinding wheel, the wheel moves rapidly until an adjustable bushing 73 supported on the outer end of the piston rod 42 engages the dash pot piston 70 which serves to retard the forward motion of the wheel while exhausting fluid through a needle valve 74. The forward grinding feed continues until a second adjustable bushing 75 engages the end of the dash pot cylinder to positively limit the infeeding movement of the grinding wheel.

In precision grinding it is necessary to allow the wheel to dwell or the sparks to die out with the wheel in contact with the work piece. This is preferably accomplished by means of a dwell control valve 80 which is connected by a pipe 81 with a chamber 82 which receives exhaust fluid passing outwardly through the needle valve 74. When the dash pot piston starts its forward movement, exhausting fluid through needle valve 74 and pipe 81, it causes an upward movement of the piston 82 which serves to rock the lever 83 pivotally mounted on a stud 84 in a clockwise direction. A pivotally mounted trigger stud 85 for a mercury switch 88. The complete details of the dwell control valve and its operation have not been illustrated since this valve is not considered part of the present invention. This valve is identical with that shown in the prior United States patent to Wood No. 1,969,997 dated August 14, 1934, to which reference may be had for a detailed illustration and description of the operation of the dwell control valve. During the forward movement of the dash pot piston 70 while fluid is being exhausted through needle valve 74 and pipe 81, the piston dwell control valve piston 82 is maintained in an upward position. When the forward movement of the piston ceases, fluid ceases to pass through the pipe 81 and the valve piston 82 moves in a downward direction under the influence of gravity at a slow rate, as controlled by a needle valve 89 which has been more fully described in the

prior Patent No. 1,969,997. Fluid exhausts from the dwell control valve 80 through a pipe 91 into a sump or reservoir 92.

During the return or rearward movement of the dash pot piston 70 under the influence of the spring 72, fluid is drawn from the reservoir 92, through a pipe 93, through a ball check valve 94 and a pipe 95 into the dash pot chamber so that the dash pot chamber is filled ready for the next grinding operation.

After the periphery of the work piece has been ground to the desired predetermined size, it is desirable to cause a relative longitudinal movement between the wheel and work piece to bring a second operative face of the grinding wheel into operative relation with a second surface, such as a shoulder, to be ground. In the preferred construction, as illustrated in the drawing, this movement is accomplished by providing a similar hydraulic mechanism for moving the work table 25 longitudinally to move the work piece 32 into operative relation with the face of the grinding wheel. This hydraulic unit is substantially identical to that above described for moving the wheel slide. A cylinder 100 is mounted on the end of the machine base 10 and carries a piston 101 which is connected by a piston rod 102 with the end of the table 25. The admission of fluid under pressure to the cylinder chambers 103 and 104 is controlled by a reversing control valve 105. This valve is identical with the valve for controlling the transverse movement of the wheel slide and consequently will not be described in detail. The valve 105 is preferably a piston type valve having a valve stem 106. Fluid under pressure is forced from pump 45 through pipe 46 into a valve chamber 107 and in the position of the valve as shown in the drawing passes through a passage 108 into the cylinder chamber 103 to cause the table 25 to move toward the right, as viewed in Fig. 1. During this movement of the table, fluid is exhausted from the cylinder chamber 104 through a passage 109, through the valve 105 and out through a pipe 59 which exhausts into the reservoir 43.

The hydraulic system is arranged so that the table 25 will move rapidly when moved toward the right to move the work piece 32 through an inoperative position. When the table is moved toward the left to move the end face 110 of the work piece into operative relation with the operative face 111 of a grinding wheel 112, it is desirable to provide a suitable control unit for precisely regulating the feed to a proper grinding feed. This is accomplished in a manner similar to that described in connection with the wheel feeding mechanism by means of a dash pot cylinder 115 which is mounted on the end of the cylinder 100 and which contains a dash pot piston 116 which is slidably mounted on the piston rod 102. The details of the dash pot mechanism will not be described, since this dash pot is identical with the dash pot shown on the wheel feeding mechanism. During the movement of the table 25 toward the left, the valve 105 is preferably arranged for either manual or automatic operation. A manually operable control lever 120 is pivotally mounted on a stud 121 which is supported on the base of the machine. The other end of the lever 120 is connected by a stud 122 with the end of the valve stem 106. When it is desired to cause a feeding movement of the table 25 to move the end face 110 of the work piece 32 into operative relation with the face 111 of grinding wheel 112, the lever 120 is moved into dotted line position 120a so that fluid under

pressure from the pipe 46 will pass through passage 109 into cylinder chamber 104 to cause the table to move rapidly toward the left to move the work into operative position with relation 5 to the grinding wheel 112. The rapid movement of the table toward the left continues until an adjustable sleeve 125 which is mounted on the outer end of the piston rod 102 engages the end of the dash pot piston 116 and causes fluid 10 to exhaust therefrom through a needle valve 126 out through a pipe 127 into a dwell control valve 128 to cause the dwell control valve piston 129 to move upwardly.

The dash pot mechanism, as controlled by the 15 needle valve 126, serves to modify the movements as produced by the piston 101 to slow down the table movement to a predetermined grinding speed or feed. The infeed toward the left continues until a second sleeve 130 on the piston 20 rod 102 engages the end of the dash pot cylinder, serving to positively limit the movement of the table 25 toward the left. When the dash pot piston is prevented from moving further, fluid under pressure ceases to pass through pipe 127 25 and the dwell control valve piston 129 moves downwardly under the influence of gravity, as controlled by a needle valve 132. The flange 133 is connected with the dwell control piston 129 and rocks a pivotally mounted lever 134 in a 30 counterclockwise direction so that the projection 135 on the lever engages a projection 136 on a mercury switch 137 and serves to rock the mercury switch so as to energize a solenoid 140 which is connected to a lever 141 fixedly mounted 35 on the valve stem 106 and shifts the control valve 105 into the position illustrated in Fig. 1 so as to reverse the fluid under pressure and pass it through a passage 108 in the cylinder chamber 103 to move the piston 101 and the table 25 40 toward the right to withdraw the face 110 of the work piece 32 away from the operative face 111 of the grinding wheel 112.

Fluid under pressure is exhausted from the dwell control valve 128, through a pipe 145, into 45 a reservoir 146. During the return movement of the dash pot piston 116 under the influence of the spring 147, fluid is drawn through a pipe 148, a ball check valve 149 and a pipe 150 into the dash pot chamber so that the chamber is 50 filled, ready for the next grinding operation. It is desirable that the relative transverse movement of the grinding wheel and the work support and the relative longitudinal movement therebetween be synchronized so that the peripheral surface 55 of the work piece will be ground to a predetermined size while the work and the wheel are moved transversely relative to each other and that the relative longitudinal movement between the wheel and the work will then be automatically 60 started to move the work piece and wheel longitudinally relative to each other to grind an end face of the work piece to the required extent. As illustrated in the drawing, electrical power is 65 taken from a source of power, as indicated by the power lines 155. In order that the wheel feeding movement and the table traversing may be synchronized to operate in the desired sequence, a solenoid 156 is connected in parallel with the solenoid 65. The solenoid 156 is connected 70 through the link 141 to actuate the reverse control valve 105 and cause it to move toward the left into a position to cause the table 25 to move the face 110 of the work piece 32 into operative relation with the face 111 of the grinding wheel 112.

In the operation of this mechanism, the wheel feed and the table operating mechanism have been previously adjusted to produce the desired feed and the stops have been set to stop the infeed and longitudinal movements thereof when the work has been ground to a predetermined extent. The work piece 32 is mounted on centers 30 and 31 and the headstock pulley 34 is started rotating. The lever 60 is then moved from the dotted line position 60a into the full line position 60 to move the valve stem 48 into the position illustrated in the drawing, so that fluid from the pipe 46 passes into the cylinder chamber 55 to cause an infeeding movement of the grinding wheel 112. As above described, the wheel first 15 moves rapidly until the dash pot mechanism is rendered effective to cause a slow grinding feed which continues until the dwell control valve piston 82 drops downwardly under the influence of gravity to trip the mercury switch 88. Tripping 20 of the mercury switch 88 makes a circuit so as to simultaneously energize the solenoids 65 and 156. The energizing of the solenoid 65 serves to remove the valve 47 into the reverse position to cause a rearward movement of the grinding wheel. The 25 energizing of the solenoid 156 serves to shift the valve stem 106 into a reverse position from that shown in the drawing to shift the lever 120 into the position 120a and to cause the fluid under pressure from the pipe 46 to pass through valve 30 chamber 107, though passage 109 to cause a feeding movement of the table 25 toward the left. The table 25 first moves rapidly until the dash pot mechanism slows down the table movement 35 to a grinding speed as the face 110 of the work piece 32 is brought into operative contact with the face 111 of the grinding wheel 112. This feeding movement continues until the fixed stop 130 limits the movement of the table toward the left and the dwell control valve piston 129 drops under the influence of gravity to trip the mercury switch 137 which makes a circuit to energize the solenoid 140 40 which shifts the control valve 106 toward the right into the position as illustrated in Fig. 1 so as to admit fluid under pressure from the pipe 46 45 through the passage 108 into the cylinder chamber 103 to cause the table 25 to move toward the right to an inoperative position.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawing is to be interpreted as illustrative and not in a limiting sense.

We claim:—

1. A grinding machine comprising a base, a rotatable grinding wheel and a rotatable work support which are arranged to be moved longitudinally and transversely relative to each other, said grinding wheel having a pair of angularly disposed operative faces arranged successively to grind a peripheral surface and an adjacent shoulder face on the work piece, precision means automatically to cause a relative transverse movement between the wheel and work support to grind the peripheral face on the work piece to a predetermined size, and a second precision means actuated in timed relation therewith automatically to move the wheel and table longitudinally relative to each 70 75

other to grind a shoulder face thereon to a predetermined extent.

2. A grinding machine comprising a base, a rotatable grinding wheel and a rotatable work support which are arranged to be moved longitudinally and transversely relative to each other, said grinding wheel having an operative face arranged to grind a peripheral surface and an end or shoulder face on the work piece, means including a fluid pressure piston and cylinder to cause a relative transverse movement of the wheel and work support a hydraulic feed regulator to control said transverse movement to grind a peripheral face on the work piece to a predetermined size, and means including a fluid pressure operated piston and cylinder which are controlled by said regulator and are operatively connected automatically to cause a relative longitudinal movement between the wheel and work support to 20 grind an end or shoulder face on said work piece to a predetermined extent.

3. A grinding machine comprising a base, a rotatable grinding wheel and a rotatable work support which are arranged to be moved longitudinally and transversely relative to each other, said grinding wheel having a pair of angularly disposed operative peripheral faces arranged to grind a peripheral surface and an end or shoulder face on said work piece, means including a fluid pressure operated piston and cylinder rapidly to move the wheel and work support transversely relative to each other, a hydraulic feed regulator associated therewith to control the infeed of the grinding wheel to grind a peripheral face on the work piece to a predetermined extent, electrically operated dwell control mechanism which is actuated by said regulator when the work piece has been ground to a predetermined size to cause a transverse relative separating movement between the grinding wheel and the work support, means including a control valve therefor which is actuated by said dwell control mechanism to control the grinding of an end or shoulder face on said work piece to a predetermined extent.

4. A grinding machine comprising a base, a rotatable grinding wheel, a transversely movable slide supporting said wheel, a longitudinally movable work supporting table, a rotatable work support on said table arranged to rotatably support a work piece, precision means including a fluid pressure piston and cylinder mechanism to feed the wheel slide transversely toward and from the work support to grind a peripheral surface on the work support to a predetermined size, a feed regulator therefor to control the rate of said transverse movement, and means including a fluid pressure piston and cylinder controlled by said regulator which are operatively connected to automatically cause a relative longitudinal movement between the wheel and work support 65 to grind an end face thereon to a predetermined extent.

5. A grinding machine comprising a base, a transversely movable wheel slide thereon, a pair of rotatable grinding wheels supported on said slide, said grinding wheels each having an operative face formed thereon, one of which is arranged to grind a peripheral surface and the other of which is arranged to grind an end or shoulder face on a work piece, a longitudinally movable work supporting table, means including

a fluid pressure operated piston and cylinder to cause a transverse movement of the wheel slide to grind a peripheral face on the work piece to a predetermined size, a hydraulic feed regulator cooperating therewith to control the infeeding movement of the grinding wheel, means including a fluid pressure operated piston and cylinder, and a control valve therefor which is actuated in timed relation with said regulator automatically to move said table longitudinally to bring an end face or shoulder on a work piece into operative relation with the second operative face on the grinding wheel to grind said surface to a predetermined extent.

6. A grinding machine comprising a rotatable grinding wheel, a transversely movable slide therefor, a longitudinally movable work supporting table, a rotatable work support on said table, a fluid pressure piston and cylinder operatively connected to move the slide transversely to cause an infeeding movement of the grinding wheel to grind a peripheral face on the work piece, a dash pot and dwell control mechanism associated with said piston and cylinder which serve to control the infeed of the grinding wheel, electrically operated means actuated by said dwell control to move the wheel slide rearwardly after the work piece has been ground to a predetermined size, and means including a fluid pressure operated mechanism controlled by said electrically operated means and operatively connected to move the table longitudinally to grind an end face on the work piece to a predetermined extent.

7. A grinding machine comprising a base, a rotatable grinding wheel and a rotatable work support which are arranged to be moved longitudinally and transversely relative to each other, said grinding wheel having an operative face arranged to grind a peripheral surface and an end or shoulder face on a work piece, means including a fluid pressure operated piston and cylinder to cause a relative transverse movement between the wheel and the work support, a control valve to control the admission and exhaust of fluid to said piston and cylinder, electrically operated means including a mercury switch actuated when the work piece is reduced to a predetermined size, a solenoid rendered operative by said switch to actuate said valve and cause a transverse separating movement between the wheel and work support, a second fluid pressure piston and cylinder operatively connected to cause a relative longitudinal movement between the wheel and work support to grind an end or shoulder face on the work piece, a control valve for said second piston and cylinder to cause a relative longitudinal movement between the wheel and work in either direction, electrically operated means including a solenoid actuated by said mercury switch to shift said second control valve to initiate a longitudinal movement between the wheel and work to move a shoulder or end face into operative relation with the face of the grinding wheel to grind the face to a predetermined extent, and electrically operated means actuated when said face has been ground to a predetermined extent to shift the second control valve and thereby cause a relative longitudinal movement between the wheel and work support in the reverse direction to separate the work piece from the operative face of the grinding wheel.

8. A grinding machine comprising a base, a transversely movable wheel slide supported

thereon, a rotatable grinding wheel supported by said slide, said grinding wheel having an operative face arranged to grind a peripheral surface on the work piece and a second operative face arranged to grind a second or end face thereon, a longitudinally movable work supporting table, a rotatable work support on said table, means including a fluid pressure piston and cylinder to move said wheel slide toward and from the work support to grind a peripheral face to a predetermined size, a dash pot and dwell control mechanism arranged to control the speed of movement of said slide toward the work and to control said grinding operation, a control valve associated with said piston and cylinder, an electrically operated mechanism actuated in timed relation with said dwell control mechanism to actuate said valve and reverse the wheel slide movement after the peripheral surface has been ground to a predetermined size, means including a second fluid pressure piston and cylinder oper-

atively connected to move said table longitudinally, a dash pot and dwell control mechanism arranged to control the speed of the longitudinal movement of said table in one direction when the table is moved to position an end or shoulder face on a work piece in operative relation with the second face on said grinding wheel, a control valve arranged to control the admission of fluid under pressure to said second cylinder, and electrically operated means including a solenoid actuated in timed relation with said first electrically operated mechanism to shift said second control valve and start the table moving in a predetermined direction to grind a second face on the work piece, and electrically operated means actuated when said shoulder or end face has been ground to a predetermined extent to cause said table to move in the reverse direction to an inoperative position.
